UNITED STATES PATENT OFFICE

155,996

DESIGN FOR A NONMETALLIC CASING FOR A WRITING INSTRUMENT

John Pinkney Gowland, Santa Barbara, Calif.

Application April 21, 1949, Serial No. 2,183
In Great Britain October 21, 1948

Term of patent 14 years

(Cl. D74—17)

To all whom it may concern:

Be it known that I, John Pinkney Gowland, a British subject and a resident of Santa Barbara, in the county of Santa Barbara, State of California, have invented a new, original, and ornamental Design for a Nonmetallic Casing for a Writing Instrument, of which the following is a specification, reference being had to the accompanying drawing, forming a part thereof.

In the drawing,

Figure 1 is a side elevational view of a nonmetallic casing for a writing instrument, showing my new design; and

Figure 2 is a top plan view of the same.

I claim:

The ornamental design for a nonmetallic casing for a writing instrument, substantially as shown.
JOHN PINKNEY GOWLAND.
